UNITED STATES PATENT OFFICE.

ROBERT W. SCOTT, OF BABYLON, NEW YORK, ASSIGNOR TO SCOTT AND WILLIAMS, INC., OF NEW YORK, N. Y., A CORPORATION OF MASSACHUSETTS.

TIMING-CLUTCH FOR DIAL AND CYLINDER KNITTING-MACHINES.

1,356,092.

Specification of Letters Patent.

Patented Oct. 19, 1920.

Application filed August 22, 1919. Serial No. 319,163.

To all whom it may concern:

Be it known that I, ROBERT W. SCOTT, a citizen of the United States of America, residing at Babylon, in the county of Nassau and State of New York, have invented certain new and useful Improvements in Timing-Clutches for Dial and Cylinder Knitting-Machines, of which the following is a specification.

10 My invention relates to rotary knitting machines of that class in which a cylinder carrying knitting needles is combined with a dial carrying coöperating knitting instruments, such as needles, as in rib knitting machines, or hooks, as in machines of the type described in my United States Letters Patent No. 1,282,958 dated Oct. 29, 1918.

The object of my invention is to so construct a knitting machine of the combined

20 cylinder and dial type that whenever desired the dial may be lifted up, to permit convenient access to the fabric or interior of the cylinder, or its needles or other parts carried by it, yet whenever the dial is re-

25 turned to position the needles or other knitting instruments carried by the dial will be caused to automatically register in coöperating relation to the knitting instruments carried by the cylinder.

30 In the accompanying drawings I have shown my invention, for the sake of illustration, as applied to a knitting machine of the general character of that set forth in my above mentioned patent.

35 Figure 1 is a front elevation partly in section on the line 1—1 of Fig. 2, with the latch guard down in its normal position;

Fig. 2 is a side elevation, with parts broken away, and showing the dial-carrying frame raised on its hinge;

Fig. 3 is a face view of one part of a form of clutch which may be used.

In these drawings, D represents a part of the knitting machine bed plate in which 45 is mounted the rotating needle cylinder 260 adapted to be driven by a bevel wheel 31 on a horizontal shaft 32. This cylinder carries the usual needles n to be raised and lowered by cams on a stationary cam cylinder C, or other suitable means.

The rotary dial 4, which carries the radially actuated knitting instruments to co-operate with the cylinder needles, may be carried by the latch guard ring 550 through

the medium of a frame 1 mounted on this 55 ring (Fig. 1). Rotary motion may be imparted to this dial in unison with the needle cylinder from the shaft 32 through a train of gears such as shown in Fig. 1. As there illustrated the train includes a bevel 33 on 60 the back of the wheel 31, and meshing into a bevel pinion 34 on the lower end of a vertical spindle 35, which carries at its upper end a pinion 36 in a gear box 42 mounted on the bed plate D. In line with the spindle 35, and above it, is another spindle 40 mounted in bearings 41 on the gear box 42, and motion is transmitted from the spindle 35 to the spindle 40 through the medium of gears 36, 37, 38 and 39, such as to transmit 70 to the dial a peripheral speed the same as that given to the ring of needles in the cylinder 260.

In connection with the spindle 40 is a bevel wheel 43 to transmit motion through 75 a bevel pinion 44, shaft 45, and bevel gears 46 and 47 to the shaft 48 carrying the dial 4, these shafts 45 and 48 being mounted in bearings on the frame 1 on the latch guard ring 550.

This latch guard ring 550, as seen in Fig. 2, is hinged as usual at 549 to a post 548 on the bed plate D in order that the latch ring may be raised up, when desired, to permit of access to the fabric being knitted or the 85 needle cylinder and the needles and other parts carried by the cylinder.

Ordinarily the machine has been so constructed that when the latch guard ring was thus raised, a pinion such as that at 44 was 90 thereby lifted out of gear with the pinion 43. This had the disadvantage that, when the latch guard ring and the parts carried by it were to be dropped down to position again, special care and manipulation by the 95 operator were necessary to see that the separated gears re-meshed in a way to bring the knitting instruments in the needle cylinder and dial into proper relation.

I overcome this disadvantage by interposing in the train of gears a one-position clutch, and I find it convenient to make this clutch the sole separating point in the train. For this purpose I interpose the clutch between the gears in the box 42 and the pinion 43. One part 50 of the clutch is secured to the upper end of the spindle 40, while the other half of the clutch 51 is secured to,

or formed in one with, the pinion 43, which turns on a pin 3 secured to the cover piece 2, mounted on the top of the frame 1.

One half of the clutch, say the part 51, 5 carries a fixed pin 52, projecting on its lower face, while the other half preferably has two projecting pins 53 and 54 (Figs. 2 and 3) beveled on their outer sides, these pins being normally held in the positions shown in 10 Fig. 2 by springs 55 on the rear face of the clutch disk, but permitting either of these pins to be pushed downward.

Thus, when the latch guard ring is dropped down to normal position, after 15 having been raised, the two parts of the clutch will become locked together only in one position, that is, when the pin 52 lies between the two pins 53 and 54. When the two parts of the clutch are brought together 20 in any other relative positions of these pins, the part 50 of the clutch will revolve without the part 51 until the pin 52 slides past one of the pins 53, 54, pushing it back by acting on its beveled face, until the pin 52 25 contacts with the vertical face of the other spring-pressed pin, whereupon the pin which had been pressed back will snap into place behind the pin 52 and cause a locking engagement.

30 I prefer to use these two spring pins, or their equivalents, so that the clutch may act no matter in which direction the machines may be revolving.

Although I have described the needle 35 cylinder and dial as the moving parts, it will be understood that my invention may be equally well applied to a rotary machine in which the cams which actuate the knitting instruments are the moving parts.

40 I claim as my invention—

1. A rotary knitting machine having a cylinder and dial, both carrying coöperating knitting instruments and gearing therefor driven from a common source, in combina-

tion with means for breaking the geared 45 connection between the dial and cylinder on lifting the dial from the cylinder and an interposed positioning clutch in the gearing, whereby on returning the dial to position, registry of the knitting instruments carried 50 by the cylinder and dial will be insured.

2. A rotary knitting machine having a cylinder and dial, both carrying coöperating knitting instruments and gearing therefor driven from a common source, in combination 55 with means for breaking the geared connection between the dial and cylinder on lifting the dial from the cylinder, and a one-position clutch interposed in the gearing for the dial, as and for the purpose described. 60

3. A rotary knitting machine having a cylinder and dial, both carrying coöperating knitting instruments and gearing therefor driven from a common source, in combination 65 with means for breaking the geared connection between the dial and cylinder on lifting the dial from the cylinder, and a clutch interposed in the gearing for the dial, one part of the clutch having a single projection, while the other has two projections 70 with outer beveled faces and spring means to let the projections snap past each other into locking engagement.

4. A rotary knitting machine having a cylinder and dial, both carrying coöperating 75 knitting instruments and gearing therefor driven from a common source, in combination with a positioning clutch interposed in the gearing and means for separating parts of the clutch on lifting the dial from the 80 cylinder, whereby on returning the dial to position, registry of the knitting instruments carried by the cylinder and dial will be insured.

In testimony whereof I have signed my 85 name to this specification.

ROBERT W. SCOTT.
